(Cl. D34—15)

To all whom it may concern:

Be it known that I, Everett Hellwegen, a citizen of the United States and a resident of the city of Long Beach, county of Los Angeles, State of California, have invented a new, original, and ornamental Design for a Hobbyhorse, of which the following is a specification, reference being had to the accompanying drawing, forming part thereof.

I claim:

The ornamental design for a hobbyhorse, as shown.

EVERETT HELLWEGEN.
